UNITED STATES PATENT OFFICE.

JOSEPH CLOONEY, OF NEW YORK, N. Y.

EXTENSION-TABLE.

SPECIFICATION forming part of Letters Patent No. 276,159, dated April 24, 1883.

Application filed February 9, 1883. (No model.)

To all whom it may concern:

Be it known that I, JOSEPH CLOONEY, of the city, county, and State of New York, have invented a new and useful Improvement in 5 Extension-Tables; and I do hereby declare that the following is a full and exact description thereof, reference being had to the accompanying drawings, and to the letters of reference marked thereon, making a part of this 10 specification.

My invention relates to extension-tables which are fitted with movable leaves connected to the sliding horizontal bars by pivoted links to admit of their depression, so as to pass under the stationary leaves when the table is 15 closed.

It has for its object greater convenience in the manipulation of the table and greater compactness when the table is folded together.

20 In its construction the movable leaves are adapted to fold at each end over upon themselves, and to be so lowered as that one set shall pass down between the central slide-bars, and the other rest upon the bars below the 25 level of the stationary end leaves to pass under the latter when the table is closed.

In the accompanying drawings, Figure 1 is 30 a perspective view of my improved extension-table partially extended, with one set of movable leaves lowered and another set folded in readiness to be lowered. Fig. 2 is a longitudinal section of the table fully extended; Fig. 3, a similar section of the same when closed; Fig. 4, a transverse section in line x x of Fig. 35 2; Fig. 5, a view of the under side of the table when opened out, and Fig. 6 a similar view of the same when closed.

40 A A are the end leaves of the table, each fixed to an end frame, B, resting upon the legs C C, secured to the corners thereof. These end frames, B B, are connected and the frame of the table completed by means of a series of parallel slide-bars, D' D² D³ D⁴, tongued and grooved to interlock and slide with overlapping joints, one within the other longitudinally, in manner as is usual in extension-tables of this class. The extension-frame is supported 45 by a leg, C', fitted to the central cross-bar under the slides. These lap-joint slide-bars are 50 adapted to close one within the other when

the ends of the table are pushed together until the stationary leaves A A meet in the center, as shown in Figs. 3 and 6, and they are attached to the end frames in such a manner as to leave a space, a, Fig. 2, between the top 55 of the bars and the under side of the end leaves slightly greater than twice the thickness of the central movable leaves, so as to allow these, when doubled and when resting upon the sliding bars, to pass freely under said end 60 leaves.

To the inner end of each of the end leaves, A A, a longitudinal strip, E, is closely hinged, so as to form, in fact, an extension of the leaf, which will admit of being turned up at pleasure, for the purpose hereinafter indicated.

Next to the stationary end leaf, A, at each end of the table, a movable leaf, F, is fitted. This leaf F is formed in three divisions, m m n. (See Fig. 4.) The central division, n, is 70 made of a length somewhat less than the width of the space left between the two inner bars, D⁴ D⁴, of the extension-frame, (see Fig. 5,) so as to admit of being dropped down between said bars, and the two outer divisions, m m, are 75 hinged to the ends of the first to fold in thereon and to extend the same when open to the width of the end leaves, A A, as shown in Fig. 4. This central division, n, of the leaf F is pivoted at each end by means of links W W to 80 the inner face of the side bars, R R, of a frame, R R', fitted to slide longitudinally between the inner bars, D⁴ D⁴, of the extension-frame, so as to permit the leaf, when folded, to be swung and dropped laterally from the level of the end 85 leaves, A A, of the table, as shown in Fig. 2, down into the frame R R', between the side bars, as shown in Fig. 3. The frame R R' slides freely longitudinally between the bars D⁴ D⁴, and is drawn out with the extension-bars by means of plates S S, made fast to the under face of each of the central bars, D², of the series, and which, extending therefrom inwardly over the ends of the frame R R', are 90 engaged by pins projecting from the frame 95 into slots cut in the plate, as shown in Fig. 5. These slots permit a slight loss of motion between the plates and frame to facilitate the adjustment of the leaf F, supported by the frame in its place in the table. When the slide-bar 100

D^2 is borne in under the leaf it carries with it the frame $R R'$ and the leaf F , pivoted thereto, and draws it out again when the table is opened.

- 5 The two central leaves, $G G$, of the table are also each formed with end pieces, $m' m'$, adapted to complete its length when opened out, and by folding in to so reduce its length as to admit of the passage of the leaf in between the side pieces of the end frames, $B B$. The central division of each leaf G is fitted with links $W' W'$, which are pivoted thereto and to the outer face of the central division, D , of the extension-bars, so as to support said leaves G up over the bars on a level with the end leaves of the table, and permit them, when required, to be swung and dropped laterally down upon the side bars in position to pass under and be covered by the end leaves, $A A$, when the table is closed.

When the table is fully extended the movable leaves—which, when opened out, are all of a uniform length with the end leaves, so as to maintain a uniform width in the entire length 5 of the table—are supported by the pivoted links on a level with the end leaves, so as to afford the requisite uniformity of level in the entire length of the table, and the leaves are all fitted and joined to present a complete finished table-top.

When it is desired to reduce the length of the table the ends of the central leaves at one end of the table are folded in to reduce their length. (See Figs. 1 and 4.) The hinged division of the end leaf is then lifted (see dotted lines, Fig. 1) sufficiently to permit the movable leaf F next thereto to swing in toward the end leaf and drop down under it in between the slide-bars $D^4 D^4$, as shown in Fig. 4. The next movable leaf G is then left free to drop down in the same direction upon the side bars, as shown in Fig. 3, and by pushing in this end of the table the first movable leaf, F , is carried with the slide-bars under the second 5 movable leaf, G , and both are inclosed by the end frame, B , and covered by the end leaf, A . If it is required to make the table yet smaller, the second central leaf may be depressed in the same manner and in the same direction as o the first, and by dropping the remaining leaf

into the space between the side bars, in manner as described, the table may be closed up until the two end leaves, $A A$, shall meet. The central movable leaves are thus neatly and compactly inclosed and enfolded within the closed table in two tiers, the one resting over the slide-bars immediately under the end leaves and the other under the first, in the central space between the slide-bars, as shown in Figs. 3 and 4. In opening the table the operation above described is reversed, and the table is readily enlarged at pleasure by elevating and opening out one or more of the central leaves.

I claim as my invention—

1. The combination, in an extension-table, with its fixed end leaves, A , frame B , and legs C , and with the outer parallel bars, D , in the extension-frame $D D' D^2$, &c., of the vertically-adjustable leaves G , the folding ends m' of said leaves, and the pivoted links W' , connecting the central section of each leaf with said bars D , whereby the folding leaves are carried and concealed within the end frames and under the fixed leaves when the table is closed, substantially in the manner and for the purpose herein set forth.

2. The combination, in an extension-table, with the fixed leaves A , frame B , and legs C at each end of the table, and with the parallel sliding bars $D' D^2 D^3 D^4$, and central stationary bars, D , in the extension-frame thereof, of the vertically-adjustable leaves F , having folding ends m , the auxiliary frame $R R'$, fitted between the inner set of slide-bars, D^4 , devices S , connecting said frame with the middle slide-bars, D^2 , and pivoted links W , connecting the middle section of each leaf with the frame $R R'$, whereby said folding leaves are carried and concealed within the auxiliary frames between the slide-bars under the fixed end leaves when the table is closed, substantially in the manner and for the purpose herein set forth.

In testimony whereof I have signed my name to this specification in the presence of two subscribing witnesses.

JOSEPH CLOONEY.
